UNITED STATES PATENT OFFICE.

JOSEPH KOENIG, OF MANITOWOC, WISCONSIN.

HEATER FOR HOT-AIR ENGINES.

Application filed March 17, 1926. Serial No. 95,357.

This invention relates to heater for hot air engines.

Objects of this invention are to provide a heater which, although it may be used in other capacities, is particularly adapted for use with hot air engines, such as those disclosed in my copending application Serial No. 28,839, filed May 8, 1925, for hot air engines.

10 Further objects are to provide a heater which will conserve the heat and permit the maximum extraction of heat from the hot gases, which will dilute the intensely hot gases with the products of combustion held 15 within the chamber, and which will rapidly circulate the products of combustion so that an intimate commingling of the intensely heated gases with the gases of a lower temperature is assured.

20 An embodiment of the invention is shown in the accompanying drawings, in which:

Figure 1 is a sectional view through the heater showing it in place upon a hot air engine with parts of the engine's cylinders 25 in section.

Figure 2 is an enlarged sectional view through the burner.

Referring to the drawings, it will be seen that a pair of cylinders 1 and 2 are indicated, 30 each provided with a plurality of pipes 3. These pipes and the upper ends of the cylinders are heated in hot air engines of the type referred to.

An inner casing 4 surrounds the upper 35 ends of the cylinders and is itself surrounded by an intermediate casing 5. An outer casing 6 completely surrounds the intermediate casing. Thus, an inner space 7 between the inner and intermediate casings, and an outer space 8 between the intermediate and outer casings is provided. The space 7 communicates freely with the interior of the inner casing 4 by means of the passageways 9. However, the intermediate casing is tightly 40 sealed against the cylinders. Thus, the products of combustion from the space within the inner casing 4 passes between the casings 4 and 5 and outwardly through the vent pipe 10. Fresh air enters the space 8 45 between the intermediate and outer casings by way of the apertures or passageways 11. This fresh air is, therefore, highly heated by 50 contacting with the hot casing 5. It passes downwardly through a pipe 12 to the burner 55 13.

This burner 13 is more fully illustrated in

Figure 2. It will be seen from this figure that the burner consists of an outer casing 14 and an inner casing 15. The heated air passes through the pipe 12 to the inner casing 60 and mixes with the fuel supplied by means of the nozzle or pipe 16 from any suitable source, such fuel may be gas, oil or other material suitable for this kind of burner.

It is to be noted that an auxiliary pipe 65 17 communicates with the space between the casings or shells 14 and 15 of the burner 13. This pipe 17, as may be seen from Figure 1, is supplied by means of a fan or blower 18. The intake pipe of the blower is indicated 70 at 19 and communicates with the space inside of the innermost casing 4. Thus the heated products of combustion are sucked into the blower and forced through the pipe 17 to the burner. This flow of gases, therefore, dilutes the intensely heated gases from 75 the burner and passes outwardly from the burner in the form of an enveloping shell surrounding the highly heated gases.

In addition to this effect, the blower maintains a rapid circulation of gases through 80 the device and insures intimate commingling of the products of combustion with the intensely heated gases.

This type of burner, therefore, will be 85 found highly efficient in the conservation of heat, and will permit the extraction of a large amount of heat by the tubes 3 and the ends of the cylinders 1 and 2 of the hot air engine. Further, the rapid circulation of 90 gases maintained by means of the blower and burner associated, as described, aids in the extraction of heat.

It will be seen that a very efficient heater for hot air engines has been provided by this 95 invention, and it will be seen further that the construction described in detail above, provides a heated space for the hot end of the air cylinders, in which a rapid circulation is maintained.

It will be seen further that the air is pre-heated and passed to the burner so that heat is not lost by continuation through the intermediate casing, but that this heat is brought back into the space within the innermost casing.

Although the invention has been described in considerable detail, such description is intended as illustrative rather than limiting as the invention may be variously 110 embodied and as the scope of such invention is to be determined as claimed.

I claim:

1. In a heater for hot air engines, the combination of a pair of air cylinders having hot ends, an inner casing surrounding the hot ends of the cylinders, an intermediate casing surrounding the inner casing and providing a space therebetween, said inner casing communicating freely with the said space, a vent pipe leading outwardly from the intermediate casing, an outer casing surrounding the intermediate casing and having apertures for the entrance of air, and a burner opening into the space within the inner casing and having an air pipe communicating with the space between the outer casing and the intermediate casing, whereby the interior of the inner casing is the hottest, the space between the inner and intermediate casing, the next hottest, and the space between the outer and intermediate casing, the coolest.
2. In a device of the class described, the combination of an air conditioning cylinder having hot tubes at one end, an inner casing surrounding such hot tubes, an intermediate casing surrounding the inner casing and spaced therefrom, said inner casing communicating freely with the space between such casing and the intermediate casing, a vent pipe opening outwardly from the

intermediate casing, an outer casing surrounding said intermediate casing and having air entrance apertures therein, a burner supplied with preheated air by means of a pipe opening through the intermediate casing into the space between the intermediate and outer casing having a blower adapted to suck the products of combustion from the intermediate casing and return them in proximity to the burner, whereby a rapid circulation of the products of combustion is assured.

3. In a device of the class described, the combination of an air cylinder for a hot air engine having a heated end, a casing surrounding such heated end, a burner communicating with the interior of said casing, means for preheating the air and supplying it to said burner, means for conducting products of combustion outwardly from such casing, and a blower communicating with the casing and with the burner for forcing the products of combustion past such burner and into the casing.

In testimony that I claim the foregoing I have hereunto set my hand at Manitowoc, in the county of Manitowoc and State of Wisconsin.

JOSEPH KOENIG.
